UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,863**, dated September 2, 1873; application filed August 9, 1873.
[Term of Patent 3½ years.]

J.

To all whom it may concern:

Be it known that I, FREDERICK WINK, of Philadelphia, Pennsylvania, have invented a Design for a Shawl-Pattern, of which the following is a specification:

The main features of the design, which is clearly illustrated by the figure in the accompanying drawing, are the parallel stripes A and B. The stripe A has an elaborately-ornamented central rib, *a*, of a character too clearly shown in the drawing to need description, and is further ornamented by shaded or blended parallel ribs, and by rows of dots, as shown. The stripe B is composed of minor parallel stripes, bars, or ribs, of different shades or colors, and of varying widths, and has also

an ornamented rib, *b*, similar to the rib *a*, adjacent to which is a row of dots.

Irrespective of the colors employed, I claim—

1. The design for the stripe A, as shown and described.
2. The design for the stripe B, as described and represented.
3. The design for the whole pattern, including the stripes A and B.

In testimony whereof I have signed my name to this specification in the presence of two subscribing witnesses.

FRED. WINK.

Witnesses:

CLINTON M. LATOURRETTE,
LEWIS T. GODFREY.
